 www.NielsenPatents.com(57) **CLAIM**

The ornamental design for a tea bottle, as shown and described.

DESCRIPTION

FIG. 1 is a top and side perspective view of a tea bottle showing my new design;

FIG. 2 is a side view thereof;

FIG. 3 is a top view thereof; and,

FIG. 4 is a bottom view thereof.

The broken lines of FIG. 1 and FIG. 2 of the drawings depict portions of the tea bottle that form no part of the claimed design.
